UNITED STATES PATENT OFFICE.

ROBERT S. ROBE, OF WATERTOWN, MASSACHUSETTS.

WASHING MACHINE.

Application filed October 9, 1924. Serial No. 742,565.

To all whom it may concern:

Be it known that I, ROBERT S. ROBE, a citizen of the United States, and resident of Watertown, county of Middlesex, State of Massachusetts, have invented an Improvement in Washing Machines, of which the following description, in connection with the accompanying drawing, is a specification, like characters on the drawing representing like parts.

This invention relates to washing machines which are especially adapted for washing clothes and other articles of a more or less absorbent nature.

15 The most efficient way to wash clothes and similar articles is by forcing the suds or other cleansing fluid through them repeatedly and it is one of the objects of the present invention to provide a washing machine 20 which operates on this principle and does not subject the clothes to any rubbing or agitating action which has a more or less destructive effect on the articles being washed.

25 In the operation of an apparatus embodying my invention the clothes or other articles to be washed are so treated that they are alternately and repeatedly saturated or filled with the suds or other cleansing fluid and then subjected to pressure to express the suds from them. In this way the suds is repeatedly drawn into the interstices in the fabrics being washed and then is forced 30 from the interstices, an operation which is effective in properly washing the clothes.

35 The preferred embodiment of the invention comprises a container or receptacle in which the articles to be washed are placed together with means for drawing the suds or other cleansing fluid into the container so that the clothes will become saturated with such suds or cleansing fluid and then forcing the cleansing fluid out of the container and out of and through the articles within 40 the container.

45 A convenient and practical construction is one in which means are provided for producing sufficient suction in the container to draw the suds or other cleansing fluid into it and then subjecting the clothes in the container to pressure to express the suds therefrom, these operations being repeated until the washing is completed. The container may have a pipe connection leading thereto which is adapted to be connected with a tank containing the suds or other

cleansing fluid so that as the suction or vacuum conditions are produced in the container the suds will be drawn by suction from the tank into the container and when 60 the pressure is developed in the container the suds will be forced from the container and through the clothes therein back into the tank again.

If it is desired to rinse and blue the 65 clothes in addition to washing them after the washing operation has been carried on for a sufficient length of time the pipe connection from the container may be connected to a tank or receptacle containing rinsing 70 water in which case the rinsing water will be repeatedly and alternately drawn into the container and into the clothes and then will be expelled therefrom thus performing 75 the rinsing operation.

For blueing the clothes the pipe connection may simply be connected to a tank containing blueing water and when this is done the blueing water will be drawn into the tank and the clothes and then expressed 80 from the clothes.

In order to give an understanding of the invention I have illustrated in the drawing a selected embodiment thereof which will now be described after which the novel features will be pointed out in the appended 85 claims.

The drawing shows partially in section a machine embodying the invention and adapted to wash clothes or similar articles. 90

The device comprises a container 1 in which the clothes 2 to be washed may be placed. This container has connected thereto a conduit or pipe 3 which communicates with a tank 4 or other receptacle containing 95 the cleansing fluid.

The tank herein illustrated is an open top tank and the end of the pipe 3 is merely inserted into the tank so as to be immersed in the cleansing fluid therein, this being a 100 simple and inexpensive way of connecting the pipe to the tank. Any other way of doing this may be employed without departing from the invention.

The device also comprises means for forcing the suds or cleansing fluid from the tank 4 into the receptacle 1 and into the clothes 2 and then expelling the cleansing fluid from the receptacle 1 back into the tank 4 again thereby forcing the cleansing fluid 110 out of and through the clothes 2. A convenient way of doing this is to provide

means for producing suction in the container 1 sufficient to draw the suds or cleansing fluid from the tank 4 into said chamber and then to produce a sufficient pressure in 5 said chamber to expel the suds or cleansing fluid therefrom.

In the construction herein shown this alternate suction and pressure is secured by providing means for alternately increasing 10 and decreasing the volume of the clothes-receiving chamber in the container. A simple way of accomplishing this is to place within the container a water tight rubber bag 5 which is connected through a suitable 15 coupling 6 to the cylinder 7 of a plunger pump, which cylinder is filled with water and has a piston or plunger 8 operating therein. This piston or plunger is connected by a connecting rod 9 to a crank disk 10, 20 which is carried by a shaft 31. The rotation of the crank disk will move the plunger or piston 8 up and down and during the upward stroke of the plunger the water in the cylinder will be forced into the rubber bag 5 thus expanding the latter and correspondingly reducing the size of the clothes-containing compartment, while when the plunger or piston 8 moves downwardly the water will be withdrawn from the bag thus 25 collapsing the latter and increasing the size of the clothes-containing compartment. The bag 5 constitutes in effect a movable partition which divides the container or casing 30 1 into the clothes-receiving compartment 35 and into another compartment within the bag into which the water or other fluid is forced under pressure.

The container 1 is shown as spherical in shape and is made in two semi-spherical 40 parts 11 and 12 which are hinged together at 13 and which may be clamped in closed position by a suitable clamp 14. The wall of the upper section 12 is perforated as shown at 15 and a hood 16 is secured exteriorly to the wall of the section 12 at the 45 perforated portion, said hood forming a chamber 17 within it which communicates with the clothes-receiving compartment through the apertures 16 and to which the 50 hose pipe 3 is connected.

Assuming that there are clothes or articles to be washed in the clothes-containing compartment and that the plunger 8 is at the upper end of its stroke with the bag 5 expanded, it will be understood that when the plunger moves downwardly and withdraws the water from the bag 5 the latter will collapse thus producing suction in the chamber 1 which will draw suds or cleansing fluid 55 from the tank 4 through the pipe 3 into the clothes-containing compartment. At the next up stroke of the plunger 8 the bag 5 will be expanded thus subjecting the clothes to pressure and forcing the suds or cleansing fluid out through the perforations 16,

chamber 17 and the hose pipe 3 into the tank 4. The continued reciprocation of the plunger 8 will thus alternately draw the suds or cleansing fluid into the clothes-containing compartment and expel it therefrom. 70

As the suds or other cleansing fluid is drawn into the compartment it will be soaked up or absorbed by the clothes and will fill the interstices in the fabrics and when the bag 5 is expanded the clothes are subjected to pressure which squeezes the suds or other cleansing fluid out of the clothes. There is thus an alternate absorption of the suds out of the clothes and the squeezing of the suds out of the clothes which is a very effective way of washing clothes, fabric or material of an absorbent nature. 80

In order to perform the washing operation most effectively it is desirable that the expanding and contracting action of the clothes-receiving compartment should be relatively slow so that the suds can be slowly drawn into and absorbed by the clothes as the clothes-receiving compartment expands and will be slowly squeezed from the clothes as said compartment is contracted. 90

The crank disk 10 may be rotated by any suitable means which will drive it at the desired speed and merely as in illustration of one suitable mechanism I have shown said crank disk as in the form of a worm gear which meshes with and is driven by a worm 18 on the shaft of a suitable motor 19. 95

In performing the washing operation it is desirable that the clothes should be subjected to approximately the same pressure at each up stroke of the plunger 8 and as the amount of water which it is necessary to force into the bag 5 to develop this desired pressure will vary as the amount of clothes in the container varies, I have provided means herein for compensating for such variation in the amount of clothes and thereby securing the desired pressure when the piston 8 is at the upper end of its stroke. 100

This is herein accomplished by mounting the motor 19 and shaft 31 on a yielding platform 20. This platform is shown as supported by springs 21 which are connected to the frame 22 by which the container is supported. These springs are so constructed and adjusted that they will yield when the desired pressure in the container 1 has been reached and, therefore, whenever during the up stroke of the piston the desired pressure in the container 1 has been developed then the springs 21 will yield as the crank disk 10 continues its rotation to carry the crank pin over the upper dead center. In this way the device will automatically adjust itself to varying amounts of clothes and the action will be the same whether a greater or a less number of clothes are in the clothes container. 110

If it is desired to rinse the clothes as well 115

as wash them I propose to employ another tank 23 containing rinsing water and into which the pipe connection 3 may be introduced after the washing is completed and when the rinsing operation is to be performed. When the pipe 3 has thus been transferred to the tank 23 then during further operation of the machine the clean rinsing water will be forced back and forth through the clothes thus rinsing them.

If it is desired to blue the clothes then a third tank 24 will be employed containing blueing water and the blueing operation may be accomplished by introducing the pipe 3 into the tank 24 and operating the machine so that the blueing water will be alternately and repeatedly drawn into the container 1 and expelled therefrom.

The use of the bag 5 produces in effect an expandible and contractible clothes-receiving chamber and it will be noted that the washing operation is carried out by simply expanding this chamber to draw the suds or cleansing fluid into it and then contracting the chamber to force the suds or cleansing fluid out of it, the suds or cleansing fluid during this operation being absorbed or soaked up by the clothes and then being expressed from the clothes by pressure.

20 I claim:

1. In a washing machine, the combination with a casing, of a movable partition dividing the casing into two chambers, one of which is adapted to receive the clothes to be washed, a receptacle for washing water, a conduit for connecting the clothes-receiving chamber to said receptacle, means for alternately forcing a fluid under pressure into the other chamber and withdrawing said fluid from said chamber, whereby the clothes-receiving chamber is alternately contracted and expanded, and during the expanding movement of said chamber the washing water is drawn from the receptacle into said chamber while during the contracting movement thereof the washing water is expelled therefrom back into the receptacle.

2. In a washing machine, the combination with a casing, of a movable partition dividing the casing into two chambers, one of which is adapted to receive the clothes to be washed, a receptacle for washing water, a conduit for connecting the clothes-receiving chamber to said receptacle, a pump device operating alternately to force fluid into the other chamber under pressure and withdraw said fluid from said chamber, whereby the clothes-receiving chamber is alternately contracted and expanded and washing water is drawn into said chamber through said conduit and then expelled therefrom through said conduit.

3. In a washing machine, the combination with an expandible and contractible chamber to receive the clothes to be washed, of

a receptacle separate from and independent of said chamber and adapted to contain cleansing fluid, a conduit connecting said chamber to said receptacle, said chamber being closed substantially air tight except at 70 said conduit, and means for alternately expanding and contracting said chamber whereby the cleansing fluid is alternately drawn into the chamber from the receptacle through said conduit and then expelled from 75 the chamber through said conduit back into the receptacle again.

4. In a washing machine, the combination with a casing, of a movable partition dividing the casing into two chambers, one 80 of which is adapted to receive the clothes to be washed, a receptacle for washing water, a conduit for connecting said clothes-receiving chamber to said receptacle, a pump device for alternately forcing fluid into said chamber under pressure and withdrawing said fluid from said other chamber whereby the clothes-receiving chamber is alternately contracted and expanded and washing water is drawn from the receptacle into the chamber during the expanding movement and is forced therefrom during the contracting movement, and means to limit the pressure developed in said other chamber by the pump device.

5. In a washing machine, the combination with an expandible and contractible chamber to receive the clothes to be washed, of a plurality of tanks, a conduit for connecting said chamber to any one of said tanks, and means for alternately expanding and contracting the chamber whereby fluid from the tank to which the chamber is connected will be alternately drawn into the chamber and expelled therefrom.

6. In a washing machine, the combination with an expandible and contractible chamber to receive the clothes to be washed, of two tanks, one containing cleansing fluid and the other containing rinsing water, 110 means for connecting the chamber to either tank, and means for alternately expanding and contracting the chamber, whereby fluid from the tank to which the chamber is connected will be alternately drawn into the 115 chamber and expelled therefrom.

7. In a washing machine, the combination with a container to receive the clothes to be washed, of a tank containing cleansing fluid with which the container communicates, of a rubber bag within the chamber, a cylinder with which said bag communicates, said cylinder being filled with a non-compressible fluid, a piston in said cylinder, and means for operating the piston whereby the bag will be alternately expanded and contracted, thereby contracting and expanding the chamber in which the clothes are received.

8. In a washing machine, the combina- 130

tion with a container having a movable wall, the space on one side of said wall constituting a clothes-receiving compartment, a cylinder communicating with the space on the other side of said wall, a piston in said cylinder, said cylinder being filled with a non-compressible fluid, a receptacle containing

cleansing fluid which has communication with said clothes-receiving compartment, and means for operating the piston.

10

In testimony whereof, I have signed my name to this specification.

ROBERT S. ROBE.
